UNITED STATES PATENT OFFICE.

ROY B. ENDECOTT, OF ROUNDUP, MONTANA.

WIRE-CUTTER ATTACHMENT FOR GUNS.

1,244,968.

Specification of Letters Patent. Patented Oct. 30, 1917.

Application filed January 30, 1917. Serial No. 145,415.

To all whom it may concern:

Be it known that I, ROY B. ENDECOTT, a citizen of the United States, residing at Roundup, in the county of Musselshell and State of Montana, have invented certain new and useful Improvements in Wire-Cutter Attachments for Guns; and I do hereby declare the following to be a full, clear, and exact description of the invention, such as will enable others skilled in the art to which it appertains to make and use the same.

This invention has for one of its objects the provision of a device of this character which may be readily attached to any standard type of gun, whereby the user of the gun will have means at hand at all times for cutting wire.

Another object of this invention is to provide a base strip secured to the gun and having cutting blades mounted thereon which are operatively connected to an operating lever, whereby upon movement of the operating lever, the cutting blades will be opened and closed to receive and sever wire or like articles.

A further object of this invention is the provision of an operating lever of such construction that a portion thereof will form a very efficient and practical trigger guard to the trigger of the gun.

A still further object of this invention is the provision of a wire cutter attachment for guns of the above stated character, which shall be simple, durable and efficient, and which may be manufactured and sold at a comparatively low cost.

With these and other objects in view as will become more apparent as the description proceeds, the invention consists of certain novel features of construction, combination and arrangement of parts as will be herein-after more fully described and claimed.

For a complete understanding of my invention, reference may be had to the following description and accompanying drawing, in which:

Figure 1 is a fragmentary side elevation of a gun having a wire cutter attachment applied thereto and which is constructed in accordance with my invention.

Fig. 2 is a detail sectional view taken on the line 2—2 of Fig. 1.

Fig. 3 is a detail sectional view taken on the line 3—3 illustrating the cutting blades,

Fig. 4 is an enlarged fragmentary sec-

tional view illustrating the means of journaling one of the rollers.

Fig. 5 is a detail sectional view illustrating a stop formed upon the arm.

Referring in detail to the drawing, the numeral 1 indicates a barrel of a gun having the usual stock 2 secured thereto and to which my invention is applied.

A base strip 3 is secured to the under side of the stock 2 and has formed thereon a downwardly depending extension 4, the forward lower edge of which is beveled to form a cutting edge 5. The cutting edge 5 of the extension 4 constitutes a stationary blade. An arm 6 has a pair of relatively spaced ears 7 formed thereon which are pivotally secured to the extension 4 adjacent the rear edge thereof and formed upon the forward end of the arm 6 is an extension 8 which has one edge thereof beveled to form a cutting edge 9 which cutting edge constitutes a movable blade. The free end of the arm 6 is bent at right angles to form a stop 10, for a purpose which will be hereinafter more fully described.

A downwardly depending ear 11 is formed on the base strip 3 and has pivoted thereto an operating lever 12, which is bent adjacent its pivot end to form a trigger guard 13 which partially surrounds the trigger 14 of the gun. Formed upon the trigger guard 13 is a handle 15 having a finger opening 16. An extension 17 is formed upon the handle 15 and is adapted to be engaged by a suitable spring pressed catch 18, carried by the stock 2. Formed upon the pivot end of the operating lever 12 is a downwardly and forwardly inclined arm 19, which has its lower end bifurcated as illustrated at 20. The bifurcated end 20 has journaled therein a ball bearing roller 21, which is adapted to travel upon the upper edge of the arm 6, permitting the bifurcated ends 20 to engage a short distance upon each side of the arm 6. A pair of links 22 are pivoted to the arm 19 as illustrated at 23 and are bent inwardly as illustrated at 24 to engage the sides of the arm 6. Journaled between the free ends of the links 24 is a ball bearing roller 21, which engages the under edge 105 of the arm 6, thus it will be seen that a connection has been provided between the operating lever 12 and the arm 6, which will easily and efficiently operate without any undue friction.

In operation, by swinging the handle 12 downwardly, the arm 6 is moved upwardly parting the movable blade from the stationary blade, thus permitting a wire or like article to be inserted between the blades and by swinging the handle 12 upwardly, the movable blade moves in engagement with the stationary blade, thus severing or cutting the wire or like.

10 While I have shown and described the preferred embodiment of my invention, it will be understood that minor changes in construction and combination of parts may be made without departing from the spirit 15 and scope of the invention as claimed.

What is claimed is:

1. The combination with a gun including a stock, of a base strip secured to the stock, a stationary blade formed on the base, a movable blade pivoted to the stationary blade, an arm formed on the movable blade, an operating lever pivoted to the base, a downwardly and forwardly extending arm formed on the operating lever, 25 means for slidably connecting the arms together, and a handle formed on the operating lever.
2. The combination with a gun including a stock, of a base secured to the stock, a stationary blade formed on the base, a movable blade pivoted to the stationary blade, an arm formed on the movable blade, an 30

ear formed on the base, an operating lever pivoted to said ear, said operating lever being bent to form a trigger guard, a handle formed on the trigger guard, an extension formed on the handle, a spring pressed catch carried by the stock, and engaging the extension to hold the handle against movement, and means for slidably connecting the 40 operating lever with the arm.

3. The combination with a gun including a stock, of a base secured to the stock, a stationary blade formed on the base, a movable blade pivoted to the stationary blade, 45 an arm formed on the movable blade, an operating lever pivoted to the base, a downwardly depending arm formed on the operating lever and having its free end bifurcated to receive the first mentioned arm, a 50 ball bearing roller journaled in the bifurcated end of the second mentioned arm and engaging one end of the first mentioned arm, links pivoted to the second mentioned arm and disposed upon each side of the first 55 mentioned arm, and a ball bearing roller journaled to the links and engaging the other edge of the first mentioned arm.

In testimony whereof I affix my signature in presence of two witnesses.

ROY B. ENDECOTT.
